LINK CHAIN FOR A BRACELET OR THE LIKE

Emil Rodriguez, New York, N.Y., assignor to Jacoby-Bender, Inc., Woodside, N.Y., a corporation of New York

Filed July 14, 1964, Ser. No. 80,848

Term of patent 7 years

(Cl. D45—4)

FIG. 1

FIG. 2

FIG. 3

FIG. 4

FIG. 5

FIG. 6

FIG. 7

FIG. 8

FIG. 1 is a top plan view of a first embodiment of a link chain for a bracelet of my new design wherein those portions of the bracelet shown unshaded are concave;

FIG. 2 is a top plan view on an enlarged scale of the far right link of FIG. 1;

FIG. 3 is a side elevational view of the top shell of the link of FIG. 2;

FIG. 4 is an end elevational view of the top shell of the link of FIG. 2;

FIG. 5 is a top plan view of a second embodiment of a bracelet of my new design wherein those portions of the bracelet shown unshaded are convex;

FIG. 6 is a top plan view on an enlarged scale of the far right of FIG. 5;

FIG. 7 is a side elevational view of the top shell of the link of FIG. 6; and

FIG. 8 is an end elevational view of the top shell of the link of FIG. 6.

The shading shown in the drawing represents contrast.

I claim:

The ornamental design for a link chain for a bracelet or the like, as shown and described.
